US00D825333S

(12) **United States Design Patent** (10) Patent No.: **US D825,333 S**
Ozamiz et al. (45) Date of Patent: ** *Aug. 14, 2018

(54) **CONTAINER CLOSURE**

(71) Applicant: **Berlin Packaging, LLC**, Chicago, IL (US)

(72) Inventors: **Katie Ozamiz**, Chicago, IL (US); **Andrew Sanguinet**, La Grange Park, IL (US); **Brett Niggel**, Corry, PA (US)

(73) Assignee: **Berlin Packaging, LLC**, Chicago, IL (US)

(*) Notice: This patent is subject to a terminal disclaimer.

(**) Term: **15 Years**

(21) Appl. No.: **29/572,164**

(22) Filed: **Jul. 26, 2016**

Related U.S. Application Data

(62) Division of application No. 29/509,788, filed on Nov. 21, 2014, now Pat. No. Des. 784,810.

CLAIM

The ornamental design for a container closure, as shown and described.

DESCRIPTION

FIG. 1 is a right side perspective view showing the new design;

FIG. 2 is a rear left perspective view thereof;

FIG. 3 is a bottom right side perspective view thereof;

FIG. 4 is a bottom left side perspective view thereof;

FIG. 5 is a right side view thereof;

FIG. 6 is a left side view thereof;

FIG. 7 is a front elevation view thereof;

FIG. 8 is a rear elevation view thereof;

FIG. 9 is a top plan view thereof; and,

FIG. 10 is a bottom plan view thereof.

The broken lines are shown for the purpose of illustrating parts of the container closure that form no part of the claim.

1 Claim, 10 Drawing Sheets
